UNITED STATES PATENT OFFICE.

CHARLES E. ALBRO, OF PHILADELPHIA, PENNSYLVANIA.

GEAR-CUTTING MACHINE.

SPECIFICATION forming part of Letters Patent No. 281,820, dated July 24, 1883.

Application filed August 2, 1882. (No model.)

To all whom it may concern:

Be it known that I, CHARLES E. ALBRO, of the city and county of Philadelphia, and State of Pennsylvania, have invented an Improvement in Gear-Cutters, of which the following 5 is a specification.

My invention has reference to cutters adapted to cut worm-gears; and it consists in a frame carrying the rotating cutter-head and mechanism to rotate said cutter, said frame being secured to the revolving master-wheel shaft of a gear-cutting machine, substantially as set forth in the patent granted to me, No. 219,892, dated September 23, 1879, and in another pending application of mine, the revolution of the frame being independent of the revolution of the cutter; further, in providing the frame with suitable mechanism whereby it may be adjusted back or forth, and thus perform its 15 function without making a complete revolution; and in many details of construction, all of which are fully set out in the following specification and shown in the accompanying drawings, which form part thereof.

25 The object of my invention is to provide a rotary cutter and adapt it to gear-cutting machines, whereby it is enabled to cut worms for worm-wheel gearing.

In the drawings, Figure 1 is a front elevation 30 of my improved gear-cutting mechanism, showing it in the act of cutting a worm. Fig. 2 is a sectional elevation of same on line $x-x$, and Fig. 3 is a side elevation of a gear-cutting machine with my improved gear-cutter attached thereto.

35 A is the frame of the gear-cutting machine. B is the master-wheel shaft, and carries at one end the master-wheel C.

Mesning with the master-wheel is the worm-gear D.

40 E is a hinged or sliding frame, and carries the shaft or mandrel I, upon which the blank to be cut into a worm is placed.

F are the train-gears, by which the relative movements or rotation of the mandrel or shaft I and master-wheel shaft B are governed.

45 H is a rack with which the pinion G, attached to the frame E, meshes to regulate the position of the mandrel or shaft I, upon which 50 the blank to be cut is placed.

K is the driving-shaft.

The foregoing is a brief description of one

form of gear-cutting machine, and is in substance similar to the patent referred to above.

To the end of the master-wheel shaft B, I secure the hub L, having the flange l.

55 M is the cutter-frame, and is arranged to fit upon the hub L, being provided with an annular projection, m' , concentric with the flange of the hub, but not fitting the periphery of the same, as an annular space, m , is left between them.

60 Through the plate or frame M, I pass bolts N', which pass through the space m and ring-plate N, which is loosely arranged over said annular space and rests upon the flange l and projection m' . By loosening the bolts N' the frame M may be turned forward or backward and adjusted upon the hub L, the bolts moving in the annular groove or space m .

70 Secured to the frame M is a bearing-casting, O, which carries the two shafts P and P', which are set at right angles to each other, the latter of said shafts being in line with the master-wheel shaft B. The shaft P' carries upon its inner end a bevel-pinion, P³, and upon its outer end a cone-pulley, P⁵. The pinion P³ meshes with the bevel-wheel P' on the inner end of shaft P, the outer end of which carries another bevel-wheel, P². This wheel P² meshes 75 with a bevel-wheel, R, held in bearing O' by collars r r, and is provided with a feather or key constructed in the usual manner, which fits the groove r' in the shaft R', which is free to slide through the wheel R, but revolves with it. 80 One end of this grooved shaft R' is supported in bearing O², and carries on its end a miter-gear, R², which meshes with its fellow R³, secured upon the end of shaft R', which gears with shaft R' by means of pinions or spur-wheels R⁵ and R⁶. These shafts R⁴ R⁷ are supported in bearings O³, which, with bearing O², 85 are secured to an adjustable plate, Q, arranged to be adjusted in the direction of the shaft R' upon the frame M by means of bolts T and slots t, or any other equivalent device, as the well-known guides and screw.

To the end of shaft R' is removably secured 90 the cutter S, the plane of revolution of which passes through the center line of the master-wheel shaft B.

J represents a worm-blank secured upon the mandrel or shaft I, and in the act of being cut.

I do not limit myself to the construction

shown, as it may be modified in various ways—as, for instance, the shaft P may gear directly with the cutter-shaft P', or the frame M may be secured directly upon the shaft B—my invention comprehending, broadly, a revolving cutter having an independent movement about a fixed center.

The operation is as follows: The machine being set in motion, after causing the rotation 10 of the cone-pulley P⁵, the master-wheel shaft B moves the frame M, with its cutter, slowly in the direction of the arrow. The relative speeds of the master-wheel shaft B and mandrel I being governed to suit the pitch of the worm to 15 be cut, the blank J is slowly rotated, the said blank and frame moving in the same relation as if they were respectively the worm and worm-wheel, and as the cutter S has an independent and more rapid rotation it cuts 20 the thread upon the blank, as shown. One passage of the cutter over the blank is sufficient to finish the thread upon the same; but if it is desired to go over it again it is readily accomplished by loosening the bolts N and 25 turning the frame M all the way around, or moving it back again. If desired, the cutter may be brought around again by continuing the action of the machine.

By this mechanism single or double threads 30 may be cut, the latter being accomplished by a double operation of the machine, or by it with two rotating cutters radiating from the center of the master-wheel shaft.

The worm cut by this machine is what is 35 technically known as the "Hindley Screw," and is one in which the outer surface of the screw or worm is curved to correspond to the periphery or root-circle of the worm-wheel with which it is to mesh.

40 The adjustable frame Q is used to regulate distance of the cutter S from the shaft B to make the worm suit any desired worm-wheel.

Having now described my invention, what I 45 claim as new, and desire to secure by Letters Patent, is—

1. A cutter for gear-cutting machines, having two motions—one a rotary motion upon its own axis, and the other an independent rotary motion about a fixed point—in combination 50 with a rotating spindle adapted to hold and rotate the gear-blank to be cut with a speed having a given relation to the rotation of the cutter about the fixed point, substantially as and for the purpose set forth.

55 2. In mechanism for cutting gearing, a frame arranged to revolve about a fixed center and provided with a revolving or rotary cutter, in combination with means to rotate said cutter, and means to rotate the frame, and a rotating spindle adapted to hold and rotate the

gear-blank to be cut with a speed having a given relation to the rotation of the cutter about the fixed center, substantially as and for the purpose specified.

3. In mechanism for cutting gearing, a frame 65 arranged to revolve or vibrate about a fixed center, and provided with a rotary cutter whose plane of revolution passes through said fixed center, in combination with independent mechanism to rotate both the cutter and frame 70 at the same time, substantially as and for the purpose specified.

4. In mechanism for cutting gearing, a frame arranged to revolve or vibrate about a fixed center and provided with a rotary cutter, in 75 combination with independent mechanism to rotate both the cutter and frame at the same time, a rotating spindle adapted to hold and rotate the gear-blank to be cut with a speed having a given relation to the rotation of the 80 cutter about the fixed center, and means to adjust said cutter to or from the fixed center, substantially as and for the purpose specified.

5. In mechanism for cutting gearing, a shaft 85 carrying on its end a frame provided with a rotary cutter, in combination with independent mechanism to rotate said cutter and frame both at the same time, a revolving mandrel or shaft upon which the blank to be cut is placed, and means to control the relative speed or 90 revolution of said mandrel and shaft which carries the cutter-frame, substantially as and for the purpose specified.

6. In mechanism for cutting gearing, a frame 95 arranged to revolve or vibrate about a fixed center and provided with a rotary cutter, in combination with a shaft to rotate said frame, means to adjust said frame upon its shaft, and independent mechanism to rotate both the cutter and shaft, substantially as and for the 100 purpose specified.

7. In mechanism for cutting gearing, a frame arranged to rotate about a fixed center and provided with a rotary cutter, in combination with a shaft to rotate said frame, means to adjust said frame upon its shaft, means to adjust said cutter to or from the fixed center, and independent mechanism to rotate both the cutter and shaft, substantially as and for the 105 purpose specified.

8. The combination of shaft B, hub L, shafts P P' R' R' R', gears P' P² P³ R R² R³ R⁵, bearings O O' O² O³, plate Q, and cutter S, substantially as and for the purpose specified.

In testimony of which invention I hereunto 115 set my hand.

CHARLES E. ALBRO.
